DESIGN FOR A NECKLACE

Maurice Duvalet, Congers, N. Y., assignor to Van Cleef & Arpels, Inc., New York, N. Y., a corporation of Delaware

Application March 23, 1949, Serial No. 1,572

Term of patent 7 years

(Cl. D45—16)

To all whom it may concern:

Be it known that I, Maurice Duvalet, a citizen of the United States, residing at Congers, in the county of Rockland and State of New York, have invented a new, original, and ornamental Design for a Necklace, of which the following is a specification, reference being had to the accompanying drawing, forming part thereof.

Fig. 1 is a front view of a necklace, showing my new design, and

Fig. 2 is a side elevation of same.

I claim:

The ornamental design for a necklace, substantially as shown.

MAURICE DUVALET.
